OIL RETURN DEVICE FOR FLOODED
EVAPORATORS

Joseph Askin and Joseph D. Lear, Buffalo, N. Y.,
assignors to Fedders Manufacturing Company,
Inc., Buffalo, N. Y.

Application November 3, 1933, Serial No. 696,521

7 Claims. (Cl. 62—126)

This invention relates to oil recovery devices for mechanical refrigeration systems of the flooded type, and it has particular reference to means for effecting the return to the compressor of oil separated in the evaporator.

In the usual header or boiler forming a part of a flooded type refrigeration system, oil separates from liquid refrigerant and its accumulation presents a problem of removal and return to the evaporator. According to the present invention, the return of separated oil is effected by means of a siphon wick, which is advantageously disposed in a suction tube connected to the compressor. In applying the invention in practical forms, the opening of the suction tube is also utilized to effect the return of gasified refrigerant, and provision is made to prevent the splashing of liquid refrigerant into such tube, without however, so decreasing the lifting power of the wick as to interfere adversely with its oil lifting function.

In the embodiments of the invention herein-after described provision is also made to guard or shield the wick from liquid refrigerant, and to create in the suction tube a partial pressure reduction, whereby the draining of the wick will be facilitated,—features which may be advantageously included in the application of the principles just above outlined.

In another aspect, the invention provides a gasified refrigerant and liquid lubricant return device, in which the parts while assembled in unitary relationship, provide for the return of refrigerant gas at a "high" or "dry" point of the evaporator, and the return of lubricant separated from the refrigerant at a "wet" or "low" point, so that the oil wick need lift the oil through only a limited distance.

The invention will be found to provide a relatively simple and inexpensive structure which is particularly devised for the space and production problems of the modern header, as more specifically described in the accompanying specification and drawing, wherein:

Fig. 1 is a longitudinal section through a header containing an oil return device forming the first embodiment of the invention;

Fig. 2 is a longitudinal section through a similar header containing an oil return device forming the second embodiment of the invention;

Fig. 3 is a perspective view showing the wick siphon of Fig. 1 on an enlarged scale; a wall of the wick is broken away to show the cross section thereof.

The drawing illustrates several embodiments of the invention, each of which is devised to be mounted within an expansion chamber or header 10, forming part of the evaporator of a refrigeration system of the well known flooded type. The header 10 may be formed in the usual manner, including a shell 11 and a head plate 12 united by a soldered joint 13 to form a closed body. Refrigerant is introduced into the header through an input fitting 14 secured to the plate 12 and a communicating passage 15. A valve 16 controls the flow through this passage, and it is controlled by a float 17 pivoted to the plate 12, and cooperating to maintain a predetermined liquid level in the header, as indicated by the numeral 18. Gasified refrigerant is withdrawn from the header through a suction conduit 19 which communicates therewith through a fitting 21 secured to the plate 12.

As thus far described, the header structure presents a well known device wherein a refrigerant-oil solution is subjected to expansion and the eventual releasing of the oil volumes to form an oil layer 22 at the liquid level 18. The oil-refrigerant ratio varies to a considerable degree in different refrigeration systems, chiefly in accordance with the lubrication demands of the type of compressor utilized, and in order to disclose the flexibility of the oil return device which forms the present invention, the embodiment 30 thereof as shown in Fig. 1 is devised for a slow rate of oil return, while that of Fig. 2, although similar in principle of operation, is devised for a relatively faster rate of oil return.

In Fig. 1 the oil return device is associated with a suction tube 23 which is secured at one end to the plate 12 in communication with the suction conduit 19. The tube is formed with a loop portion 24 which depends through the oil layer 22 and terminates in a vertical terminal portion 25 disposed above the liquid level 18. Oil is withdrawn from the oil layer 22 and conveyed into the terminal portion 25 of the tube 23 by a siphon device 26, which is preferably in the form of a cylindrical wick (Fig. 3) consisting of a cylindrical leg 27 disposed about the exterior of the terminal portion 25 and an integral delivery leg 28 disposed within the terminal portion 25 and having a greater axial length.

The extremity of the wick leg 27 extends into the oil layer 22 where it is operative to withdraw oil by capillary action for upward disposal to the delivery leg 28, whence, due to gravitational effects, it finally drips from the extremity of the 55

longer wick leg 28 into the tube 23 for eventual direction to the suction conduit 19.

The leg 21 of the wick and the tube terminal 25 are shielded by an enclosing tube 29 which extends from approximately the liquid level to the top of the header, to provide a substantial continuation or extension of the suction tube.

In actual operation the placid condition of the liquid level 18, which may be inferred from the drawing, is not continuously maintained, as turbulence ranging from a slight wave effect to violent eruption is a frequent occurrence as occasioned by ebullition in response to physical and thermal shocks in the refrigerator. The close proximity of the tube terminal 25 to the liquid level 18, therefore, incurs the danger of flooding during such periods, and the introduction of liquid refrigerant into the suction line; which danger is obviated by the provision of the tube extension 29 which in effect raises the input end of the suction line to the top of the header and out of the danger zone. The tube extension 29 has the further functions of protecting the wick during such periods; of enclosing the wick leg 21 between its wall and the annular wall of the tube end 25 to increase or improve the capillary action therein; and also in insuring that the warmest gases (which naturally segregate at the top of the header) be first directed to the suction conduit. In its latter aspect, the suction tube 23 and the extension tube 29 may be considered a single conduit wherein a wick or wicks are interposed at a point adjacent the liquid level in the header.

In Fig. 2, a suction tube 31, of larger cross sectional area than that of Fig. 1, is secured to the plate 12, and it is similarly formed with a depending loop portion 32 terminating in a vertical terminal portion 33, extending above the liquid level 18. A siphon wick 34 is mounted over the extremity of the terminal portion and it is similar in disposal to the described wick 26, having an exterior cylindrical leg 35 and an integral interior leg 36. An extension tube 37 is fitted within the interior leg 36 of the wick in light engagement therewith. A shield or skirt member 38 is secured to the exterior of the tube 37 and it is formed with a flared portion 39 which depends downward to encompass all but the lower extremity of the exterior wick leg 35. The extremity 41 of the skirt member may terminate immediately above the liquid level 18 as shown, or it may be spaced at a greater distance from the liquid level.

The operation of the embodiment of the invention shown in Fig. 2 will be found to be similar to that of Fig. 1 during idle or "off cycle" periods of operation of the refrigeration system. Under this condition the siphon action of the wick 34 will be aided by the walls of the skirt 38 and tube 37 to withdraw oil from the header for delivery into the loop portion 32 until the liquid levels therein and in the header are coincident. Upon resumption of the operation of the compressor 65 the suction head is resumed in the suction line, whereupon any oil deposited in the loop portion 32 is withdrawn.

During the operation of the compressor, the gas drawn through the tube extension 37 and past the lower end thereof will tend to create an area of low pressure about the lower extremity of the inner wick leg 36, whereupon the siphoning action of the wick will be supplemented to a considerable degree. As a result, aside from

proportional considerations, the oil delivery characteristics of the wick siphon 34 are comparatively greater than those of the wick siphon 26 of Fig. 1 during "on cycle" periods of operation of the refrigeration system.

With regard to the choice of material for the wick siphons, it will be noted that due to the partial enclosure thereof in the structures described, the danger of detached particles entering the refrigerant system is curtailed to a considerable degree. In view of this, cotton or other textile materials may be used therefor, providing their structure is not subject to deterioration by the refrigerant. It is preferred, however, to form the wicks out of fine bronze screening of between 100 and 150 mesh and of one or more thicknesses, dependent upon the rate of oil return desired.

It will be obvious from the foregoing that a rigid standard cannot be established in oil return devices, since conditions of operation and lubrication problems vary with different types of equipment; therefore, it is intended that the described embodiments of the invention be considered as exemplary of structural applications of the general principles set forth, which may be varied within the scope of the following claims.

We claim:

1. In a refrigerating apparatus comprising a header having an inlet for admitting oil and refrigerant for gravitational separation into an oil layer and refrigerant body, means for maintaining a substantially constant liquid level in the header below the top thereof, a suction tube mounted within the header and formed with a looped portion depending into the liquid and having its open extremity terminating in close proximity to the top of the header, and a siphon device communicating with the oil layer in the header and entered in said tube at a point below said open extremity thereof and adjacent to the liquid level.

2. In a refrigerating apparatus comprising a header having an inlet for admitting oil and refrigerant for gravitational separation into an oil layer and a refrigerant body, a suction tube mounted within the header and being formed with a looped portion depending into the liquid and having its extremity terminating in close proximity with the top of the header, said suction tube being formed of two parts disposed in telescoped relation at a point adjacent to and above the liquid level, and an oil return wick entered in the oil layer in the header and interposed between the telescoped parts of the suction tube.

3. In a refrigerating apparatus comprising a header having an inlet for admitting oil and refrigerant for gravitational separation into an oil layer and a refrigerant body, a suction tube mounted within the header and formed of a looped tube depending into the liquid and having its extremity extending upward and terminating adjacent to and above the oil layer, and an extension tube disposed in telescoping relation with the extremity of the looped tube and extending upward in the header to a point adjacent the top thereof, and an oil return wick entered in the oil layer and interposed between the telescoped parts of the suction tube.

4. In a refrigeration apparatus comprising a header having an inlet for admitting oil and refrigerant for gravitational separation into an oil layer and a refrigerant body, a suction tube mounted within the header and formed of a looped tube depending into the liquid and having its ex-

5. In a refrigeration apparatus comprising a header having an inlet for admitting oil and refrigerant for gravitational separation into an oil layer and a refrigerant body, a suction tube mounted within the header and formed of a looped tube depending into the liquid and having its extremity extending upward and terminating adjacent to and above the oil layer, and an extension tube disposed in telescoping relation with the extremity of the looped tube and extending upward in the header to a point adjacent the top thereof, a cylindrical wick having one portion engaged about the exterior of the looped tube and entered in the oil layer and its opposite portion disposed within the looped tube and terminating at a point lower than the liquid level in the header, whereby said wick provides a siphon to withdraw oil from the header for delivery into the looped tube.
6. In a refrigeration apparatus comprising a header having an inlet for admitting oil and refrigerant for gravitational separation into an oil layer and a refrigerant body, a suction tube mounted within the header and formed of a looped tube depending into the liquid and having its extremity extending upward and terminating adjacent to and above the oil layer, and an extension tube disposed in telescoping relation over the extremity of the looped tube and extending upward to a point adjacent the top of the header, and a cylindrical wick having one portion engaged between the telescoped tubes and entering the oil layer and a remaining portion disposed within the looped tube and terminating at a point lower than the liquid level in the header, whereby said wick provides a siphon to withdraw oil from the header for delivery into the looped tube.
7. In a refrigerating apparatus comprising a header having an inlet for admitting oil and refrigerant for gravitational separation into an oil layer and a refrigerant body, a suction tube mounted within the header and formed of a looped tube depending into the liquid and having its extremity extending upward and terminating adjacent to and above the oil layer, a cylindrical wick having one portion engaged about the exterior of the looped tube and entering the oil layer and a remaining portion disposed within the looped tube extremity and terminating at a point lower than the liquid level in the header, and a cylindrical shield enclosing the wick on the interior and exterior of said looped tube extremity.
8. In a refrigerating apparatus comprising a header having an inlet for admitting oil and refrigerant for gravitational separation into an oil layer and a refrigerant body, a suction tube mounted within the header and formed of a looped tube depending into the liquid and having its extremity extending upward and terminating adjacent to and above the oil layer, a cylindrical wick having one portion engaged about the exterior of the looped tube and entering the oil layer and a remaining portion disposed within the looped tube extremity and terminating at a point lower than the liquid level in the header, and a cylindrical shield enclosing the wick on the interior and exterior of said looped tube extremity, said shield having a tubular extension disposed vertically in the header and terminating adjacent the top thereof to provide a gas input device.
